WORK POSITIONER

Edward V. Cullen, Chicago, Ill., assignor to Cullen-Friestadt Company, Chicago, Ill., a corporation of Illinois

Application August 21, 1943, Serial No. 499,559

6 Claims. (Cl. 29—288)

The present invention relates generally to work positioners. More particularly the invention relates to that type of positioner which is especially designed or adapted to support and hold metallic structural pieces or other work in different positions in connection with welding thereof and comprises a supporting structure and in addition a work supporting and retaining table which is carried by the structure so that it is rotatable about its own center and is also capable of being tilted bodily into different angular positions as well as raised or lowered.

The primary object of the invention is to provide a work positioner of this type, which, because of the design and construction of the supporting structure therefor, has greater capabilities of use than previously designed positioners, and is capable of not only being used more expeditiously but also of handling structural assemblies, or work pieces, which are too large or bulky to be handled by conventional or standard work positioners. The improved work positioner is characterized by the fact that the supporting structure comprises: (1) a rigid elongated boom type frame having one end thereof pivotally mounted so that it is permitted to swing upwards and downwards about a substantially horizontal axis, and embodying at its other or distal end the rotatable and tilttable work supporting and retaining table; (2) an upstanding mast adjacent the proximal end of the frame; and (3) a rigid link type element having one end thereof pivotally connected to the central portion of the frame and its other end adjustably connected to the upper end of the mast, and serving to retain the frame in the various positions into which it is swung. By employing a mast and having the link type element extend between the central portion of the frame and the upper end of the mast the space beneath the frame is entirely unobstructed and hence such space may be utilized to accommodate a large-sized work piece when the table is in its inverted position in connection with the welding of the bottom portion of the work piece. Another advantage in arranging the link type element so that it extends between the central portion of the frame and the upper end of the mast resides in the fact that the frame may be lowered to substantially a horizontal position in order to facilitate mounting of the work piece on the table.

Another object of the invention is to provide a work positioner which occupies but a comparatively small amount of space, is both rugged and durable, effectively and efficiently fulfills its intended purpose and because of the specific man-

ner in which the boom type frame is adjustably supported it is capable of handling small as well as large sized work pieces.

Other objects of the invention and the various advantages and characteristics of the present work positioner will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a side elevation of a welding positioner embodying one form of the invention;

Figure 2 is a plan view of the welding positioner of Figure 1, parts being broken away and other parts being shown in section for purposes of illustration;

Figure 3 is an enlarged vertical section on the line 3—3 of Figure 2;

Figure 4 is a fragmentary vertical section of a welding positioner embodying a second or modified form of the invention; and

Figure 5 is an end view of the welding positioner of Figure 4.

The positioner which is shown in Figures 1 to 3, inclusive of the drawings constitutes or represents one embodiment of the invention. It is primarily designed for holding in different angular positions metallic structural pieces or other work in connection with welding thereof, and as its main parts comprises a base 6, an elongated frame 7, a link 8, a bracket 9 and a work supporting and retaining table 10. The base, frame, link and bracket form or constitute a supporting structure whereby the table 10 is mounted or carried so that it is capable of being raised or lowered, tilted angularly to a limited extent, and rotated about its center.

The base 6 is in the form of a fabricated structural steel unit and is adapted to rest upon, and be bolted to, the floor of the room or other enclosure in which the positioner is used. It is rectangular, as shown in Figure 2, and comprises a pair of parallel laterally spaced channel beams 11. The ends of the beams 11 are cross connected by way of a pair of metallic plates 12 and the ends of these plates rest upon, and are riveted or welded to, the top flanges of the beams. The base 6 is provided at one end thereof with a vertically extending mast 13. This mast consists of a pair of parallel laterally spaced channel beams 14 and projects upwards from the central portion of one of the

plates 12. The lower end of the mast is welded or otherwise rigidly secured to the subadjacent plate 12 in order that the mast is in fixed or rigid relation with the base 6. The central portions and lower ends of the channel beams 14 are cross connected by way of plates 15 and these are welded to the flanges of said beams 14.

The frame 7 overlies the base 6 and embodies a pair of parallel laterally spaced complementary arms 16 and 17 of channel beam design or construction. It is elongated, as shown in Figure 2, and in addition to the arms 16 and 17 it embodies a top plate 18 and a bottom plate 19. The top plate extends across the upper central portions of the two frame arms and is welded at its ends to the central portions of the upper flanges of the arms. The bottom plate 19 underlies the top plate and extends across the lower central portions of the arms 16 and 17. The ends of the bottom plate lap and are welded or otherwise fixedly secured to the central portions of the bottom flanges of the two frame arms. The ends of the arms 16 and 17 that are at one end of the elongated frame 7 are arranged in straddled relation with the mast 13 and are pivoted by way of pairs of brackets 20 and pivot pins 21 so that the frame is permitted to swing upwards and downwards about a horizontal axis or hinge line. The brackets 20 are fixedly secured to the plate 12 that underlies and supports the mast 13 and embody upstanding lugs 22. The pivot pins 21 are carried or supported by these lugs and extend through holes in the adjacent ends of the frame arms 16 and 17. By reason of the construction and arrangements of the pivotal connections which are formed by the lug equipped brackets 20 and the pivot pins, the frame 7 is permitted to swing downwards into a position wherein it is in substantially parallel relation with the base 6. The two frame arms are preferably tapered from the central portions thereof to their ends (see Figure 1).

The link 8 serves as a medium for supporting the frame 7 in the various positions into which it is swung or angularly adjusted. One end of the link extends between a pair of laterally spaced upstanding lugs 23 on the central portion of the top plate 18 of the frame 7 and is pivotally connected to such lugs by way of a pin 24. The latter extends through aligned holes in the lugs and the adjacent end of the link and permits the link to swing in a vertical plane with respect to the frame 7. The other end of the link is disposed between the upper ends of the channel beams 14 of the mast 13 and has a longitudinal series of equidistantly spaced holes 25. A pin 26 extends between the upper ends of the mast beams 14 and is mounted in diametrically opposite or coaxial holes 26a in such ends of the beam so that it is capable of being slid longitudinally out of its operative position. This pin is adapted, as shown in Figure 1, to extend through any one of the holes 25 in the link 8 and when in place it serves so to connect the hole equipped end of the link to the upper end of the mast that the link supports the frame 7. It is contemplated that an overhead crane or hoist will be employed to raise or lower the frame 7 in connection with angular adjustment of the latter. When, for example, it is desired to swing the frame upwards the operating part of the crane or hoist is applied to the distal end of the frame 7. Thereafter the pin 26 is slid axially out of engagement with the link 8. As soon as the pin is in its inoperative position the crane or hoist is operated so as to swing upwards

the frame 7. When the frame is adjusted to the proper or desired angular position the crane or hoist is stopped. Thereafter the pin 26 is slid axially into interlocked relation with the adjacent hole 25. After the pin is in place the crane or hoist is disconnected from the distal end of the frame. Upon disconnection of the crane or hoist from the frame the frame is supported by the mast 13 and the link 8. The pin 26 and the longitudinal series of holes 25 in the link 8 constitute releasable means for securing the frame 7 in its various adjusted positions. A curved plate 27 is located beneath the pin 26 (see Figure 1). This plate is welded to the upper ends of the beams 14 of the mast 13 and serves to prevent the link 8 from falling to the bottom of the mast upon withdrawal of the pin 26 in connection with angular adjustment of the frame 7.

The bracket 9 is in the form of a one-piece casting and, as hereinafter described more in detail, constitutes a mount whereby the work supporting table 10 is supported so that it is rotatable about its center and also tiltable into different angular positions. It is disposed between the outer or distal ends of the arms 16 and 17 of the frame 7 and is supported by way of a pair of coaxial horizontally extending trunnions 28 and 29 so that it, together with the table, is capable of being tilted bodily into different angular positions. The trunnion 28 is fixed to, and projects inwardly from, a socket 30 at the distal end or outer extremity of the frame arm 16 and has a longitudinal bore 31 therein. The inner end of the trunnion 28 fits within a bearing type socket 32 in the bracket 9. The other trunnion, i. e., the trunnion 29, is fixed within, and projects inwardly from a socket 33 in the distal end of the arm 17 of the frame 7 and is solid, as shown in Figure 2. The inner end of the trunnion 29 fits within a bearing type socket 34 in the bracket 9. The two trunnions, as heretofore indicated, permit the bracket 9, together with the table, to be swung about a horizontal axis.

The table 10 is adapted to carry or support the work and has a plurality of holes therein whereby the work may be removably secured to it by way of bolts or other attaching devices. It is preferably flat and has a stub shaft 35 fixed to the central portion of its under face. This stub shaft fits within a bearing 36 on the central portion of the bracket 9 and together with the bearing forms a pivotal connection whereby the work supporting and retaining table 10 is permitted to rotate about its center.

In addition to the various parts heretofore described the positioner which is shown in Figures 1 to 3, inclusive, comprises power mechanism 37 for tilting the bracket 9 and the table 10 relatively to the frame 7 and also power mechanism 38 for rotating the table 10 about its center.

The mechanism 37 comprises an electric motor 39 and speed reducing gearing 40. The motor is mounted on the central portion of the arm 16 of the frame 7 and is located on the outside of the arm. The speed reducing gearing 40 of the power mechanism 37 comprises a worm 41, a worm gear 42, a pinion 43, a gear 44, a pinion 45 and a gear segment 46. The worm 41, the worm gear 42, the pinion 43 and the gear 44 are disposed within a housing 47 which is fixed to the frame arm 16. The worm 41 is fixed to the armature shaft of the electric motor 39 and meshes with the worm gear 42. The latter is mounted on a shaft 48 which extends horizontally and is mounted in suitable bearings in the housing 47. The pinion

43 is fixed to the shaft 48 and meshes with the gear 44. The latter is mounted on one end of a shaft 49 which extends between the frame arms 16 and 17 and is carried by bearings on the arms. The pinion 45 is fixed to the central portion of the shaft 49 and meshes with the gear segment 46. As shown in Figure 2, the segment 46 is bolted to the bracket 9. When the motor 39 is driven in one direction it operates through the medium of the gearing 40 to swing the bracket and table in one direction. When the motor is reversely driven it operates through the medium of the gearing 40 to swing the bracket and table in the opposite direction. The teeth of the gear segment 46 extend throughout an arc of approximately 180°. The segment is so positioned with respect to the bracket 9 that the table is capable of being tilted from a position wherein it overlies and extends in substantially parallel relation with the distal end of the frame 7 to an inverted position wherein it underlies the distal end of the frame. Suitable limit switches (not shown) are employed to stop the electric motor 39 automatically when either end of the gear segment 46 approaches the pinion 45.

The power mechanism 38 for rotating the work supporting and retaining table about its center comprises an electric motor 50 and speed reducing gearing 51. The motor 50 is located outwards of the outer end of the trunnion 28 and is connected to such end of the trunnion by way of a housing 52. The gearing 51 of the power mechanism 38 comprises a pinion 53, a gear 54, a worm 55, a worm gear 56, a pinion 57 and a ring gear 58. The pinion 53 is mounted in the housing 52 and is fixed to one end of the armature shaft of the electric motor 50. The gear 54 meshes with, and is driven by, the pinion 53 and is mounted on one end of a horizontally extending shaft 59. Such shaft, as shown in Figure 2, extends through and is journaled in the bore 31 in the trunnion 28. The worm 55 is located between the inner ends of the trunnions 28 and 29 and is fixed to the inner end of the shaft 59. It is disposed in a recess or chamber in the bracket 9 and meshes with the worm gear 56. The latter is connected to one end of a shaft 60 which is journaled in a bearing forming part of the bracket 9. The pinion 57 is fixed to the other end of the shaft 60 and meshes with the ring gear 58. Such gear surrounds the stub shaft 35 and is fixed to the bottom face of the table 10. When current is supplied to the electric motor 50 of the power mechanism 38 the motor operates through the medium of the speed reducing gearing 51 to rotate the work supporting table 10 about its center.

When the positioner of Figures 1 to 3, inclusive, is to be used the frame 7 is swung downwards into its lowermost position in order to bring the work supporting and retaining table 10 in close proximity to the subjacent end of the base 6. Thereafter the work to be welded is placed on the table by way of an overhead crane or hoist. As soon as the work is properly positioned with respect to the table it is bolted to the latter. Thereafter the frame 7 is swung upwards, as hereinbefore described, in order to position the table at the proper elevation for welding. When the table is supported at the desired elevation it may be tilted as desired by operation or actuation of the power mechanism 37. It also may be rotated bodily about its center by actuation of the power mechanism 38.

The aforementioned positioner is both rugged

and durable and effectively and efficiently fulfills its intended purpose. It is characterized by the fact that the frame permits the table to be raised and lowered throughout an extremely great range of movement. By reason of the fact that the supporting structure includes the pivoted elongated frame 7 the work to be welded encounters no obstructions when the table is in an inverted position regardless of the elevation of the table. Because the space under the boom type frame 7 is unobstructed the frame may be lowered into a substantially horizontal position when it is desired to use the table for welding small sized work pieces. As shown in Figure 1 of the drawings the upper end of the mast 13 is substantially coplanar with the table 10 when the table is horizontally positioned and is lowered to its fullest extent. Because of this the elongated mast does not interfere with the welding of large sized pieces on the table.

The welding positioner which is shown in Figures 4 and 5 of the drawings constitutes a second or modified form of the invention. It is exactly the same as the welding positioner of Figures 1 to 3, inclusive, with the exception that it embodies power means for raising and lowering the frame instead of the link 8 and pin 26. As shown in Figure 4, the modified form of welding positioner comprises a base 61 and an elongated frame 62. The base 61 corresponds to, and is the same in design as, the base 6. The frame 62 is like the frame 7 and is pivotally connected at one end thereof. The distal end of the frame is provided with a work supporting and retaining table (not shown) which corresponds to, and is supported like, the table 10. The base 61 is provided with a pair of vertically extending laterally spaced masts 63. The latter are fixedly or rigidly connected to the base and are positioned between the pivotal connections for the arms of the frame 62. The mechanism for raising and lowering the frame 62 comprises a bracket 64 which is disposed between the upper ends of the masts 63 and is provided with a pair of oppositely extending horizontal trunnions 65. The latter fit in suitable bearings at the upper ends of the masts and permit the bracket 64 to swing or tilt about a horizontal axis. The bracket includes a platform 66 beneath the trunnions and a pair of horizontally extending parallel laterally spaced bars 67. The latter are located between the inner ends of the trunnions 65, as shown in Figure 5. In addition to the bracket 64 the mechanism for raising and lowering the table supporting frame 62 comprises an electric motor 68, a worm 69, a nut type worm gear 70 and a screw shaft 71. The motor 68 is mounted on the platform 66 of the bracket 64 and is arranged so that the armature shaft thereof extends in parallel relation with the axis of the trunnions 65. The worm 69 is fixed to one end of the armature shaft and is disposed beneath the bars 67. It overlies the platform 66 and meshes with, and serves to drive, the worm gear 70. The latter is located between the bars 67, as shown in Figures 4 and 5 and embodies an internally threaded hub 72. One end of the shaft 71 is pivotally connected to the central portion of the frame 62 and the other end of the shaft extends through aligned holes 73 in the central portions of the bars 67 and fits within the internally threaded hub 72 of the worm gear 70. When the electric motor 68 is driven in one direction the worm gear 70 is rotated in one direction and operates through the medium of the screw thread connection be-

tween its hub and the distal end of the shaft 71 to shift the shaft longitudinally in one direction. When the motor 68 is reversely driven it operates through the medium of the worm 69 reversely to rotate the worm gear 70 and such reverse rotation on the part of the worm gear operates through the medium of the aforementioned screw thread connection to shift the shaft 71 longitudinally in the opposite direction. When the motor is rotated in one direction the table carrying frame 62 is raised and when the motor is reversely driven the frame is caused to lower. The mechanism including the motor 68, the worm 69, the worm gear 70 and the shaft 71 constitutes simple power means for raising or lowering the frame 62 to any desired extent. The gearing consisting of the worm 69 and the worm gear 70 is irreversible and hence when the motor 68 is at rest the frame 62 is locked against swinging movement relatively to the base 61.

The invention is not to be understood as restricted to the details set forth since these may be modified within the scope of the appended claims without departing from the spirit and scope of the invention.

This application is a continuation in part of an application for United States Letters Patent filed by me on June 16, 1941, Serial No. 398,197.

Having thus described the invention what I claim as new and desire to secure by Letters Patent is:

1. In a work positioner comprising a rigid elongated boom type frame having one end thereof pivotally mounted so that it is permitted to swing upwards and downwards about a substantially horizontal axis, and having at its distal end a work supporting and retaining table and a mount for supporting the table so that it is capable of being rotated about its center and also tilted back and forth between a position wherein it overlies said distal end of the frame and an inverted position wherein it underlies said distal end of the frame, the combination of an upstanding mast positioned adjacent the proximal end of the frame, and a rigid link type element positioned wholly on the upper side of the frame, having one end thereof pivotally connected to the central portion of the frame and its other end adjustably connected to the upper end of the mast, and serving to retain the frame in the various positions into which it is swung.

2. In a work positioner comprising an elongated base structure, a rigid elongated boom type frame overlying the base structure and having one end thereof pivotally connected to one end of said base structure so that it is permitted to swing upwards and downwards about a substantially horizontal axis, and having at its distal end a work supporting and retaining table, and a mount for supporting the table so that it is capable of being rotated about its center and also tilted back and forth between a position wherein it overlies said distal end of the frame and an inverted position wherein it underlies said distal end of the frame, the combination of an upstanding mast connected rigidly to said one end of the base structure and positioned adjacent the proximal end of the frame, and a rigid link type element positioned wholly on the upper side of the frame, having one end thereof pivotally connected to the central portion of the frame and its other end adjustably connected to the upper end of the mast, and serving to retain the frame in the various positions into which it is swung.

3. In a work positioner comprising a rigid elongated boom type frame having one end thereof pivotally mounted so that it is permitted to swing upwards and downwards about a substantially horizontal axis, and embodying at the distal end thereof a work supporting and retaining table and a mount for supporting the table so that it is capable of being rotated about its center and also tilted back and forth between a position wherein it overlies said distal end of the frame and an inverted position wherein it underlies said distal end of the frame, the combination of an upstanding mast positioned adjacent the proximal end of the frame and having the upper end thereof bifurcated, and means for retaining the frame in the various positions into which it is swung consisting of a rigid link positioned wholly on the upper side of the frame, and having one end thereof pivotally connected to the central portion of the frame and its other end positioned in the bifurcated upper end of the mast and provided with a longitudinal series of transverse holes, and a pin extending transversely across and removably mounted in said bifurcated upper end of the mast and adapted to fit within any one of the holes in the other end of the link.

4. In a work positioner comprising a rigid elongated boom type frame having one end thereof pivotally mounted so that it is permitted to swing upwards and downwards about a substantially horizontal axis, and embodying at the distal end thereof a work supporting and retaining table and a mount for supporting the table so that it is capable of being rotated about its center and also tilted back and forth between a position wherein it overlies said distal end of the frame and an inverted position wherein it underlies said distal end of the frame, the combination of a rigid upstanding mast positioned adjacent the proximal end of the frame, and mechanism for swinging the frame into different angular positions disposed wholly on the upper side of the frame and embodying a screw shaft having one end thereof pivotally connected to the central portion of the frame and its other end positioned adjacent the upper end of the mast, a rotatable nut mounted on said other end of the shaft and operatively connected to the upper end of the mast so that it is free to tilt relatively thereto while at the same time it is confined against axial displacement, and power means associated with said upper end of the mast for rotating the nut in either direction.

5. In a work positioner comprising an elongated base structure, a rigid elongated boom type frame overlying the base structure and having one end thereof pivotally connected to one end of said base structure so that it is permitted to swing upwards and downwards about a substantially horizontal axis, and embodying at its distal end a work supporting and retaining table and a mount for supporting the table so that it is capable of being rotated about its center and also tilted back and forth between a position wherein it overlies said distal end of the frame and an inverted position wherein it underlies said distal end of the frame, the combination of a rigid upstanding mast fixedly connected to said one end of the base structure at a point adjacent the proximal end of the frame, and mechanism for swinging the frame into different angular positions disposed wholly on the upper side of the frame and embodying a screw shaft having one end thereof pivotally connected to

the central portion of the frame and its other end positioned adjacent the upper end of the mast, a rotatable nut mounted on said other end of the shaft and operatively connected to the upper end of the mast so that it is free to tilt relatively thereto while at the same time it is confined against axial displacement, and power means in the form of a reversible electric motor and speed reducing gear associated with said upper end of the mast and serving to rotate the nut in either direction.

6. In a work positioner comprising a rigid elongated boom type frame having one end thereof pivotally mounted so that it is permitted to swing upwards and downwards about a substantially horizontal axis, and embodying at its distal end a work supporting and retaining table and a mount for supporting the table so that it is capable of being rotated about its center and also

tilted back and forth between a position wherein it overlies said distal end of the frame and an inverted position wherein it underlies said distal end of the frame, the combination of an upstanding mast positioned adjacent the proximal end of the frame, having the upper end thereof of such height that the upper extremity thereof is substantially coplanar with the table when the latter is horizontally disposed above the distal end of the frame while the frame is lowered into a substantially horizontal position, and a rigid link type element positioned wholly on the upper side of the frame, having one end thereof pivotally connected to the central portion of the frame and its other end adjustably connected to the upper end of the mast, and serving to retain the frame in the various positions into which it is swung.

EDWARD V. CULLEN.
